UNITED STATES PATENT OFFICE.

LUDWIG SCHUPMANN, OF AIX-LA-CHAPELLE, ASSIGNOR TO THE URANIA-UHREN UND SÄULEN-COMMANDIT-GES. BRESLAUER & DR. VON ORTIL, OF BERLIN, GERMANY.

DESIGN FOR A CASING FOR URANIA COLUMNS.

SPECIFICATION forming part of Design No. 21,865, dated September 27, 1892.

Application filed June 8, 1892. Serial No. 436,030. Term of patent 14 years.

To all whom it may concern:

Be it known that I, LUDWIG SCHUPMANN, a subject of the King of Prussia, residing at Aix-la-Chapelle, in the Kingdom of Prussia, 5 Germany, have invented and produced a new and original Design for a Casing for Urania Columns, of which the following is a specification.

Figure 1 of the drawings represents a perspective view of a column embodying my new design. Figs. 2, 3, 4, and 5 are detail views, on a larger scale, illustrating the four upper corners of the column.

Similar letters indicate corresponding parts 15 throughout the several views.

The socle *a* of the column is substantially in the form of a quadrangular prism with flattened corners, terminated at its upper end by a somewhat-projecting ornamental molding *a'*. The shaft *b* of the column is made similar in cross-section to the socle *a* and extends from the latter to the prominently-projecting main molding or cornice *c*. About midway with respect to the height of the column are located, in relief, representations of lions' heads, (marked *d* in the drawings.)

The ornamental portion directly above the cornice *c* is substantially uranographic in design. Four masks *e* are distributed at the

four corners, representing, respectively, the 30 fixed stars, the planets, the satellites, and the comets. On the foreheads of these masks are represented the characteristic symbols of these bodies. The sun is represented by a young smiling woman with corona; the moon, 35 Fig. 2, by an old man, whose beard terminates in waves, indicating the relation to ebb and flow; earth, Fig. 4, is characterized by ears of corn and fruits, while the mask representing the comets, Fig. 5, is provided with a helmet 40 and with snakes instead of hair. Above these masks and supported upon candelabrum-pillars is represented a Saturn's ring *f*, embracing a celestial globe *h*, with zodiac *g*. The globe is surmounted by an ornamental head 45 or top piece *i*, supporting a star *j*.

What I claim as new, and desire to secure by Letters Patent, is—

The design for the casing of a urania column, as herein described and shown. 50

In testimony whereof I have signed my name to this specification in the presence of two subscribing witnesses.

LUDWIG SCHUPMANN.
